UNITED STATES PATENT OFFICE.

DANIEL VANDEWATER, OF RIVERTON, WASHINGTON.

GRINDING ATTACHMENT FOR LATHES.

1,148,729.

Specification of Letters Patent. Patented Aug. 3, 1915.

Application filed February 13, 1915. Serial No. 7,950.

To all whom it may concern:

Be it known that I, DANIEL VANDEWATER, a citizen of the United States, residing at Riverton, in the county of King and State 5 of Washington, have invented certain new and useful Improvements in Grinding Attachments for Lathes, of which the following is a specification.

This invention relates to grinding attachments for lathes or other machines, and, more particularly, designed for grinding and polishing the inside surfaces of cylinder bores.

The object of the present invention is to provide simple, inexpensive and efficient 15 grinding appliances which may be quickly applied to or detached from an ordinary machine lathe.

With these ends in view, the invention consists of a holder for the work secured to 20 the lathe carriage, a tool carrier secured to the face-plate of the lathe and adjustable diametrically thereof and having a spindle, a sleeve having at one end the emery wheel or an equivalent, and means for rotating 25 said member and the wheel independently of the orbital movement thereof which is afforded to the face-plate by the usual lathe driving mechanism.

The invention further consists in the novel 30 construction and adaptation of the various parts, as will be hereinafter described and claimed.

The invention is illustrated in the accompanying drawings, wherein Figure 1 is a 35 front elevation of a lathe with my improved grinding devices applied thereto. Fig. 2 is an end elevation of the grinding devices proper attached to the face plate of the lathe and showing the rotary driving 40 connections. Fig. 3 is a detail sectional view through 3—3 of Fig. 1. Fig. 4 is a view partly in front elevation and partly in longitudinal section illustrating the mounting of the rotary sleeve on the spindle. Fig. 5 is a transverse sectional view 45 through the face-plate and the tool-carrying plate and showing the manner of adjustably securing the latter to the face-plate.

Referring to the drawings, 6 represents 50 the lathe-bed, 7 the head-stock, 8 the face-plate mounted upon an arbor 9 which is rotated by a suitable driving means including a belt 10 passing about cone pulleys 11 and 12 of the lathe and a power-driven 55 counter-shaft 13.

14 indicates the carriage movable longitudinally on the lathe-bed 7 through the

agency of feeding mechanism such as commonly employed.

In carrying out my invention, the work 60 W, representing the cylinder of an automobile engine which is to be internally ground is secured in axial alinement with the so-called live-center of the lathe, as by bolts 15, to the vertical member 15¹ of a 65 holder whose horizontal member is secured to the carriage 14.

16 represents a disk flange of a shank 17 which terminates in a tapering spindle 18. Rotatable on said spindle and preferably 70 journaled on bushings 19 provided thereon is a sleeve 20 which is closed at its outer end and terminates in a screw-threaded stud 21. 22 represents a cup-shaped emery wheel which is secured axially upon said stud by 75 means of a nut 23. The referred-to bushings are desirably of brass and the annular space between the bushings may be filled with Babbitt or other suitable anti-friction metal to furnish a relatively large bearing 80 surface to the sleeve.

Seated in a T-shaped groove 24 extending diametrically across the face-plate 8 are the heads of bolts 25 which pass through holes 26 provided in the shank-flange 16. These 85 bolts also extend through eyes provided in ends of adjustment bolts 27 which, in turn, extend through apertures provided in posts 28. The posts 28 are formed with screw-threaded portions 28¹ fitted in holes provided in the face-plate and are rigidly secured to the latter by nuts 29.

The bolts 25 and 27 are each screw-threaded to respectively receive nuts 25¹ and 27¹. The shank 17, together with the spindle 95 18 which is integral therewith, is adjustable radially of the face-plate by regulating the nuts 27¹ and, when thus adjusted to provide the requisite eccentricity of the spindle with respect to the axis of the face-plate, the nuts 25¹ are screwed hard against the adjustment bolts to rigidly retain the flange in juxtaposition with the face-plate. 100

30 represents a finger-piece secured to the shank 17 by bolts 31 and has an inwardly 105 directed end 30¹ which engages in a circumferential groove 20¹ provided in the sleeve. This finger serves to prevent any axial movements of the sleeve with respect to the spindle; but to take up the wear in the 110 sleeve's tapering, journal, the finger is made adjustable by the provision of a longitudinal slot 30² to accommodate the bolts 29.

Formed or provided on the sleeve 20 is

- a pulley element 20² for a belt 32 which receives its motion from a driving pulley 32¹ on a second counter-shaft 13¹, having a relatively high speed.
- 5 In view of the eccentricity of the axis of pulley 20¹, the same must be rotated while revolving about the axis of the face-plate. Accordingly, I provide compensating means for obviating the belt-slack due to such orbital travel. Such means comprise a guide-pulley 33, and a tightener 34 which is supported, as shown in Fig. 2, by vibratory arms 35 and yieldingly held against the belt by a helical spring 36 or equivalent devices.
- 10 15 In grinding the interior of a cylinder, it is advantageous to remove the material which is ground from the same, for which purpose I employ a power driven suction fan, indicated by 37, which is connected with one 20 of the cylinder's port openings by a pipe 38. The operation of the invention is as follows: The cylinder or work W which is to have its bore ground, is secured to the holder 15 so as to have the axis of the cylinder in alinement with the axis of the face-plate 8. The posts 28 are secured to the face-plate by means of the nuts 29. The flange 16 is then secured to the face-plate by the bolts 25 and with the adjustment 30 bolts 27 introduced through said posts. In such relative positions, and with the nuts 25¹ slightly withdrawn, the operator manipulates the nuts 27¹ to cause the flange 16 to be moved, subject to the guiding of the bolts 25 by the groove 24, to an extent that the distance of the axis of the spindle 18 from the axis of the face-plate, together with the radius of the grinding wheel 22, will equal the radius of the cylinder-bore 35 when ground. Being thus regulated, the nuts 25¹ and 27¹ are screwed tight down to securely hold the flange to the face-plate. The belts 10 and 32 are then rendered operative to rotate the face-plate and sleeve 40 45 20. The work is thereupon brought forward with the carriage so as to be subject to the grinding wheel 22, and is in like manner progressively fed until the grinding cut is completed.
- 50 55 60 What I claim, is—
1. The combination with a face-plate and means for rotating it, of a spindle, means provided on an end of the spindle whereby the same may be rigidly secured to said face-plate for supporting the spindle from such end only and in eccentric position with respect to the face plate, a sleeve rotatably mounted on said spindle, a grinding wheel secured to said sleeve, and power-driven means for rotating the sleeve and the grinding-wheel during the orbital travel of the same about the axis of said face-plate.
  2. The combination with a face-plate and means for rotating it, of a spindle having a flange at one end, means for adjustably moving the spindle with respect to the axis of said face-plate, means extending through said flange and the face-plate for rigidly securing said spindle in such adjusted positions, a grinding wheel carried by said spindle, and means to rotate the grinding wheel during its revoluble travel about the axis of the face-plate.
  3. A cylinder-grinding attachment for lathes, which consists of a tapering spindle provided with a flange, means for adjustably securing said flange to the face-plate of a lathe, a sleeve mounted to rotate upon said spindle, a pulley formed upon said sleeve, a grinding wheel secured to the outer end of said sleeve, and a power-driven belt engaging said pulley to effect the rotation of said grinding wheel.
  4. A cylinder-grinding apparatus, comprising, in combination, a lathe, a counter-shaft, operative connection between said counter-shaft and said lathe, a face-plate for the lathe, a spindle adjustably secured to said face-plate, a sleeve mounted to rotate upon said spindle, a grinding wheel secured upon the outer end of said sleeve, a belt-pulley formed upon said sleeve, a belt-pulley upon said counter-shaft, a belt operatively connecting said belt-pulleys, a tightener-wheel for said belt, and means for holding a cylinder in axial alinement with that of the face-plate.
  5. In a cylinder-grinding apparatus, in combination, a lathe, a face-plate therefor, a counter-shaft, operative connection between said counter-shaft and said face-plate, a carriage for the lathe, a spindle adjustably secured to said face-plate, a sleeve mounted to rotate upon said spindle, a grinding wheel secured to the outer end of said sleeve, a belt-pulley formed upon said sleeve, a belt-pulley upon said counter-shaft, a belt operatively connecting said belt-pulleys, a tightener for said belt, a work-holder, means for securing said work-holder upon said carriage, means for securing a cylinder to said work-holder, means for progressively moving said carriage and work-holder toward said spindle, and a suction fan adapted to withdraw the particles produced by the grinding ahead of said grinding wheel.
- Signed at Seattle, Wash., this 2nd day of February, 1915.
